UNITED STATES PATENT OFFICE.

ELIAS E. RIES, OF BALTIMORE, MARYLAND, ASSIGNOR, BY DIRECT AND MESNE ASSIGNMENTS, TO RIES & HENDERSON, OF SAME PLACE.

ELECTRICAL-RAILWAY SYSTEM.

SPECIFICATION forming part of Letters Patent No. 409,237, dated August 20, 1889.

Application filed January 9, 1886. Serial No. 188,082. (No model.)

To all whom it may concern:

Be it known that I, ELIAS E. RIES, a citizen of the United States, residing at Baltimore, in the State of Maryland, have invented certain new and useful Improvements in Electrical-Railway Systems; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to electric-railway systems of that class in which either the track-rails or extra conducting-rails convey the electric current from stationary generators to wheels, brushes, wipers, or other electrical collectors in frictional contact with said rails and connected with electric motors mounted upon cars and employed to propel the same upon the track.

One of the objects of my invention is to provide for storing up electrical power during the running of the cars in such manner that the power so stored may be used for propelling the cars when from any cause the motors on the cars are prevented from receiving the ordinary supply of current through the conducting-rails. For these purposes a secondary battery is used, not only because it furnishes a means of guarding against the accidental interruption of the main current and propelling the cars under such circumstances, but also permitting the cars to travel without additional or exterior power upon extensions, sidings, or branches of the main road not supplied with electrical conducting-rails, as hereinafter more fully described.

The chief circumstances under which the motors on the cars will be deprived of their supply of electrical current through the conducting-rails are as follows: first, when certain sections or portions of the conducting-rails are submerged by freshets or overflows—as, for instance, in low-lying districts or when the conducting-rails are arranged in conduits in which water accumulates from rains, melting snow, defective drainage, or extraordinarily high tides through sewers connected

with the conduits. In either of these cases arrangement should be made whereby the submerged portions of the conducting-rails should be cut out of circuit and the circuit completed around them, as fully described and illustrated in Patent No. 352,265, dated November 9, 1886, for improvement in electrical railways. Such cut-out sections being temporarily incapable of contributing electrical motive power to the motors on the cars, the application of my present invention, as hereinafter described, becomes highly desirable.

When the cars of electrical railways are intended to run occasionally and temporarily upon branch roads, sidings, or extensions which are not provided with conducting-rails, it is desirable that the cars be provided with an independent motive power by which they may be propelled upon such branches, sidings, or extensions, and by my invention this necessary independent motive power is supplied.

It frequently occurs that accidental interruptions in the supply of current from the generating-station may result from accident to or temporary failure of the generating-dynamo, and to guard against this danger or failure of the current from any cause and suspension of traffic which would result it is usually customary and necessary to have a duplicate or reserve set of generating-machines for use in such emergencies. This will not be necessary in the use of my system, as sufficient current is stored at all times to insure the operation of the motor for a considerable length of time after the main current is interrupted.

My invention is especially useful in insuring a constant and reliable supply of current for operating the electric brakes of the cars. It is well understood that when electric brakes are operated by means of a current derived from the track or other conducting-rails, when removable contact or current collecting devices are used for furnishing current to the motors on the cars, the brake devices are powerless to act when the current to the motors is interrupted, and it is just under such circumstances that the brake

power is most often needed—such, for instance, as would be the case in suspending the operation of the motor on a downgrade. With the accumulators arranged as in my present invention such a contingency cannot occur, and the brakes can be applied (preferably in the manner shown in my application, No. 181,808, pending herewith) at any moment, whether the car is running or stopping, from an independent and local source of current and without employing the main propelling or track current.

My invention consists, mainly, in providing the cars with secondary or accumulating batteries and suitable devices whereby a certain proportion of the current furnished by the conducting-rails is caused to charge said secondary or accumulating batteries, and whereby the current from said batteries may at the proper times be utilized for operating the motors or for the several other purposes hereinbefore indicated.

The invention will be fully understood from the following particular description, in connection with the accompanying drawings, in which—

Figure 1 is a vertical longitudinal section on the line $x-x$, Fig. 2, through a portion of a conduit inclosing an electrical-railway conducting-rail, a portion of which traverses a depressed or low-lying portion of the route, such low-lying or depressed portion being liable to overflow and required at times to be cut out of circuit, and at such times incapable of furnishing current to motors on the cars on the track. Fig. 2 is a horizontal section of the conduit and a side chamber on the line $x'-x'$ of Fig. 1. Fig. 3 is a diagram illustrating the principle of construction in Figs. 1 and 2. Fig. 4 is a cross-section of the conduit, the road-bed, and the car on the track of an electrical railway using two conducting-rails in the conduit. Fig. 5 is a combined horizontal section and plan view of a car on the track and provided with a motor, secondary or accumulating batteries, and devices for effecting the charging of said batteries and connecting the same with the motor, as required. Fig. 6 is a vertical sectional view of a portion of an electrical railway and car upon the same, illustrating an extension of the road beyond the point at which the conducting-rail terminates. Fig. 7 is an enlarged diagram illustrating the switching devices and circuits employed in charging and applying the secondary or accumulating batteries when used upon a car, as shown in Fig. 5. Fig. 8 is another diagram of the devices for charging and applying the secondary batteries on the cars.

In Figs. 1, 2, and 3 I have simply intended to show a construction of a portion of an electrical railway in which the motive power is ordinarily supplied to the motors or the cars through the medium of conducting-rails, sections or portions of which rails may at times, owing to overflows or freshets, be ren-

dered incapable of supplying the necessary current, and at which times an independent motive power is desirable, as supplied by my present invention. In these three figures the letter a indicates the side walls of a conduit supposed to be arranged longitudinally between the surface track-rails of an electrical railway. The conduit is covered at the top by curb-plates b , resting upon the conduit-walls and having their inner edges separated, as at c , by a space or slot, through which the wipers or collectors from the cars on the railway extend into the conduit and come in contact with the conducting-rail d , which is mounted upon a non-conducting foundation e at the bottom of the conduit. As shown in Fig. 1, a section d' of this conducting-rail between the points y and y' is severed at each end from the main portion of the conducting-rail and is bridged by an insulated wire, loop, or cable f , the ends of which are connected with the main conducting-rail at opposite ends of the detached intermediate section. This bridge or loop is preferably located inside of the conduit and supported by pins g , though of course the loop may be differently located so long as it accomplishes the object of making metallic connection between the portions of the main conducting-rail at opposite ends of the detached section. This detached section of the conducting-rail traverses a low-lying district, in which water is liable to accumulate in the conduit, submerge the rail, and necessitate the cutting out of the submerged portion, so that some other means will be necessary for supplying current on the cars traversing this portion of the road. At one side of the conduit, at its lowest portion, where the cross-section is taken on the line $x'-x'$, is a side chamber having outer side wall a' , inclined bottom wall a^2 , and a removable top plate b' . In this side chamber and fastened against one of the walls of the conduit is a water-tight box h , from one wall of which projects a metallic pin i , connected with the wire loop or cable f by a conductor k , a portion of which passes through the wall of the conduit, as shown in dotted lines. From the wall of the conduit a metallic pin l projects within the water-tight box and has pivoted to it a metallic switch-arm m , which is normally pressed against the pin i by a spring n . The pin l is connected with the detached section d of the conducting-rail by means of an insulated conductor k' , (shown in dotted lines as embedded in the conduit wall and foundation e of the conducting-rail.) In the wall of the water-tight box h is a stuffing-box o , through which plays a pin p , the inner end of which is arranged opposite the switch-lever m , while its outer end is arranged to receive the pressure of the upper end of a bent lever q , which is pivoted at its elbow to a projecting lug of the box h and has secured to its lower downwardly-inclined arm a float r . The conduit is connected with side chamber by an opening through the lower

part of the conduit-wall at *s*. Normally the float *r* will rest on the bottom wall of the side chamber or suitable stop, thus allowing the spring *n* to force the switch-lever *m* into contact with the metallic pin *i*. By referring to the diagram Fig. 3 it will be seen that thus the detached rail-section *d'* is brought into metallic connection with the main portion of the conducting-rail, and now if a motor on a car were connected with the rail-section *d'* through the medium of a wiper-brush or collector said motor would receive the direct electrical current which is supplied through the conducting-rail from a stationary generator located at any suitable point on the line of the road, the return-circuit in this case being supposed to be formed by one of the surface or track rails or the earth. If the parts were to remain in this position and the low-lying rail-section *d'* should become either wholly or partially submerged by water accumulating in the conduit, it is obvious that the electrical current will be diverted from the conducting-rails to the earth, and the motors on the cars would not receive a sufficient portion of current to operate them at any point of the line of the railway.

By the invention described in my application of even date for improvement in electrical railways provision is made for cutting out of circuit the submerged section of the conducting-rail and for completing the circuit around it between those portions of the conducting-rail which are not submerged, for as soon as the water shall rise sufficiently high in the conduit to come in contact with the conducting-rail, as indicated by the dotted lines *Z Z*, it will raise the float *r*, causing the lever *q* to press inwardly the pin *p*, which forces the switch-lever *m* out of contact with the pin *i*, thus breaking metallic connection between the rail-section *d'* and the main portion of the conducting-rail, so that the current, instead of being diverted to the earth, will travel from one portion of the main conducting-rail to the other by way of the loop or cable *f*. When a low detached section of the conducting-rail is thus cut out of circuit, the cars upon the corresponding portion of the track will of course be deprived of their supply of current from the conducting-rails direct, and must be propelled by some supplementary means, which it is one of the objects of my present invention to supply.

In my present drawings, Fig. 5, I have illustrated a car traveling upon an electrical railway supposed to be provided with two conducting-rails located in a conduit, said car being provided with an electrical motor for propelling it under the influence of an electrical current derived from the conducting-rails, and said car being also provided with secondary or accumulating batteries and switching devices for effecting the charging of the same by a portion of the current derived from the conducting-rails, said switching devices being also adapted for applying the current of the

secondary or accumulating batteries to the motor for actuating the same to propel the car when the motor is deprived of current from the conducting-rails direct, provision being made also for applying the secondary-battery current to other purposes, hereinbefore referred to.

Fig. 4 may be regarded as a cross-section of Fig. 5, looking in the direction of the arrow, with the end wall of the car removed.

The letter *C* indicates the car, in a front compartment of which is located an electrical motor *M*, the shaft *S* of which in the present instance is by a driving-chain connected to drive a sprocket-wheel secured to one of the axles of the car provided with the wheels *w w*, and thus propel the car. Any other suitable intermediate connections may be used, however, between the motor-shaft and the car-wheels.

The conducting-rails in the conduit are marked with the signs +, (positive,) and -, (negative,) and in order that the motor may be supplied with current for driving it its brushes 8 and 9 are connected with these conducting-rails by the collectors and other intermediate devices, which will be more conveniently understood by referring to the enlarged diagram Fig. 7, in which most all of the parts shown are identical with the parts shown in Fig. 5. As the parts are shown in this diagram the car is supposed to be driven by the motor while deriving its current from the conducting-rails in the ordinary manner, the secondary batteries in the meantime being charged and made ready for use when required. In contact with the conducting-rails in the conduit are two metallic wheels numbered 1 and 17, which are carried by metallic arms *t t'*, insulated from each other and pivoted to arms or studs *t t'*, projecting downward from the under side of the car-floor, as shown in Fig. 4, and connected with bolts 16 on the upper side of the floor of the car. From the bolt 16 a conductor 2 leads to a contact-plate 3, and from the bolt 16' a conductor 15' leads to a contact 14. The contact-plate 3 is at present connected by a metallic bar *B* with another contact-plate 4, and the contact-plate 14 is connected by a metallic bar *B'* with another contact-plate 13, these bars *B* and *B'* being carried by but insulated from a sliding bar *D*. The contact-plate 4 is by a conductor 12 connected with another conductor 6, leading to a support 7, to which is connected one of the brushes 8 of the motor. The other brush 9 is attached to a support 10, from which a conductor 11 leads to another conductor 12, which is connected directly with the contact-plate 13. As the parts now stand it will be seen that in the ordinary running of the car the current will flow from the positive conducting-rail through the several conductors enumerated in order to the brush 8 of the motor and thence through the commutator of the motor, in the usual manner, to the brush 9, and through the other enumerated

ated conductors to the negative or return rail, thus establishing the circuit through the motor to propel the car. At the same time a portion of the current flows over the conductor 18 to 5 and through the section 19 of the accumulating-battery, passing thence over a conductor 20 to a metallic spring 23, in contact with a similar spring 24, from which a conductor 25 leads to and through another section 27 of the 10 accumulating-battery, passing thence over a conductor 29 to one end of a pivoted metallic lever 30, which by a suitable spring is normally held in contact with a metallic plate 31, from which a conductor 33 leads to the 15 conductor 12. Thus it will be seen that while the car is traveling a portion of the supplied current passes through both sections of the accumulating-battery and will charge the same, the two sections 19 and 27 being, as will 20 be seen, at such time connected in series with each other through springs 23 24 and other conductors. This serial connection will sub- 25 sist while the two sections of the accumulating-battery are being charged, and farther on it will be seen how the sections are discharged for operating the motor. When the accumulating-battery has received its full charge, it will energize the magnet M' , which is in a derived circuit therewith, by means of a back- 30 flow of current, (indicated by the arrows,) causing said magnets to attract the armature 32, thus breaking connection between lever 30 and the contact-plate 31 and interrupting the charging-circuit, the resistance R being 35 so regulated that the main charging-current passing through the magnet M' will not be sufficient to energize it, operate the armature 32, and cut out the batteries; but when the battery is fully charged the backflow from it 40 will augment the main-line current so that it will operate the magnet and cut the battery out of the charging-circuit. The batteries, it will be noted, as their charge from the main line increases, increase their resistance also, and thus divert a greater portion of the main current through the magnet until the battery is fully charged and the resistance is at the maximum. The main current, although of course stronger than the current 45 returned from the secondary battery, will not operate the magnet M' until the resistance of the battery is increased; but, on the other hand, the battery is amply sufficient to retain the armature, because it has no opposing current to overcome. The accumulating-battery being now fully charged, we will suppose that the car has arrived at a point where the conducting rail or rails are submerged, or from some other cause do not supply current to the 50 motor, and the secondary-battery current is to be applied for operating the same. At such time the switch-bar D is to be pushed upward in the direction of the arrow No. 2 until its insulating-head d separates the 55 springs 23 and 24, and the bar B breaks connection between the plates 3 and 4 and establishes it between plates 42 and 43, and

the bar B' breaks connection between the plates 13 and 14 and establishes it between 35 and 36, as shown in dotted lines. The main circuit from the conducting-rails will thus by this action be disconnected from the motor, and the sections of the accumulating-battery will be connected in series with the motor for operating the same, the current flowing in the reverse direction from said sections as follows: over the conductors 18 6, brush 8, through the motor, brush 9, conductors 11 12, (and the switch-lever 30 being attracted by magnet M'), over conductor 34, 80 plate 35, metal bar B' , plate 36, conductor 37, conductor 29, through section 27, over conductor 39, plate 42, metallic bar B , plate 43, conductor 44, into the opposite ends of section 19 of the accumulating-battery, whence 85 it started. The current from the accumulating-battery thus passing through the motor will operate it to propel the car, and when 90 said car has again reached the portion of the track where the conducting-rails supply the current the switching devices may be restored to their original positions, as first described, and the car will be propelled in the regular manner by a current supplied through the conducting-rails, a portion of which current 95 will be applied, as described, for recharging the battery.

In the arrangement of conductors as above described the resistance at R is to be so regulated that the charging-current will not energize the magnet M' sufficiently to cause it to attract its armature, as before described.

In the foregoing arrangement it has been necessary to change the switches by hand when for any reason it has become necessary that the accumulators, instead of the conducting-rail current, should operate the motor. In the organization shown in Fig. 8, however, I have illustrated an automatic combination of switching devices for effecting the charging and applying of the accumulators which may be used in place of the arrangement heretofore described. The main feature of this automatic arrangement is the switch composed of the double solenoid having two oppositely-wound sections 35' and 43', of equal power, arranged to operate upon and normally hold in equilibrium a core K , carrying a bar D' , having metallic cross-bars B and B' arranged to connect contact-plates 3' 4' and 12' 11', respectively, and the bar B being also arranged to at certain times connect contact-plates 48' and 49' when the bar is drawn downward by the solenoid V . In this arrangement the spring S holds the bar D' normally in the position shown, a suitable stop s preventing the bar from being drawn farther by the spring. The conductors 2 and 15' lead from the collector-connections 16 and 16' on the car-floor, the same as in Figs. 5 and 7, the conductor 2 terminating at the plate 3' and 15' at the plate 12'. As the parts are shown in the drawings, the car is supposed to be running and the current

supplied to the motor from the positive conducting-rail. The current passing from this rail over the positive collector and conductor 2 to plate 3' goes thence over cross-bar B, 5 plate 4', conductor 5', brush 8', motor M', brush 9', conductor 10', plate 11', cross-bar B', plate 12', conductor 15', and to the negative conducting-rail. A portion of the current goes also over conductor 14' to the series of 10 accumulators A, thence over conductor 18' to a pivoted lever 21', over said lever to a contact-plate 22', thence over a conductor 23' to the conductor 10', and on to the negative rail, as before. A stop s' holds the lever 21' 15 in the position shown against the stress of spring S', so as to complete the charging-circuit. A portion of the current branches from the conductor 14', passes over the conductor 24', through the solenoid V', over conductors 20 25' and 26' to the conductor 18', there joining with the charging-circuit going to the negative conducting-rail, the resistance R⁴ being regulated to prevent such an amount 25 of current from flowing through the solenoid V' as will draw down its core. The manner of automatically breaking the charging-circuit will be presently explained.

In the normal condition of affairs, when the core K of the double solenoid holds the 30 bar D' and metallic cross-bars B and B' in position to maintain the contacts, as shown in full lines, the two sections of the double solenoid are traversed by currents of equal power, which act upon the core K and hold it 35 in equilibrium—that is, a portion of the current flows from the conductor 2 over the conductor 37' to an insulated metallic portion 38' of the lever H, which is pivoted at h, and from this metallic portion to a contact-plate 40 39', thence over a conductor 40', through the lower section 43', and thence over a conductor 44' to the conductor 15', and on to the negative conducting-rail. At the same time a portion of the current branches from the 45 conductor 24' and passes over conductor 30' to a metallic contact-plate 31', which is supported by the arc-plate 33', and, passing from this contact-plate to an insulated metallic portion 32' of the lever H, goes thence over 50 conductor 34' through the upper solenoid-section 35', and back over conductors 36' 26' to conductor 18', where it joins the return-current on its way to the negative rail.

The resistance R⁵ is so regulated as to 55 equalize the currents between the two solenoid-sections. In this figure the lever lettered H represents the similarly-lettered lever in Figs. 4, 5, and 6, and is supposed to be the lever by means of which the collectors are 60 brought into and out of contact with the conducting-rails. In the position in which the lever is shown in Fig. 8 it will be understood that the said collectors are in contact with the conducting-rails and the car propelled by the 65 main current derived through the said collectors.

As long as the accumulators are not fully

charged the resistance of the battery will be less than the resistance R⁴, and the main portion of the incoming current will pass through 70 the battery and charge the same; but when the battery has become fully charged and its resistance so increased as to exceed the resistance R⁴ the main portion of the current will be diverted to the solenoid V' and cause 75 it to draw downward or inward its core, so as to move the lever 21' out of contact with the plate 22' and break the charging-circuit.

If in the course of operation of the apparatus the charge of the secondary battery 80 falls below its maximum, the current supplied to solenoid V' will become sufficiently weak to allow the spring S' to draw the core of the solenoid, together with the switch-arm 21', up to its normal position, whereby the 85 secondary battery will be again included in the charging-circuit. If, now, in this condition of affairs the car reaches a portion of the track where the conducting-rails are submerged or for any other reason fail to furnish 90 the current to the motor, they also fail to furnish it to the lower section of the double solenoid V, and therefore the core of said solenoid will be drawn downward by its upper section, which is in a constantly-closed 95 derived circuit with the accumulators when said accumulators are discharging, as will be readily seen. The core K and the switch-bar D' being drawn downward, the cross-bar B breaks connection between the plates 3' 4', 100 and the bar B' breaks connection between the plates 11' and 12', while the upper bar B, as shown in dotted lines, connects the plates 48' and 49'. The current from the accumulators will therefore be automatically applied to the 105 motor to drive the same and propel the car, said current flowing as follows: over the conductors 14' and 5' to the brush 8', through the motor to the brush 9', thence over conductors 10' 23', plate 22', conductor 50', plate 49', cross-bar B, plate 48', conductors 47' and 18', and into the opposite end of the series of accumulators. The car will then be propelled by the current from the accumulators until said car again reaches a point at which the current can be derived from the conducting-rails, when the lower section of the double solenoid will again be energized and counteract the action of the upper section, so that the switch-bars will be restored to the position 115 shown in full lines, the accumulators connected in the charging-circuit, and the car be driven by the main current in the ordinary manner.

If while the car is being driven by the 125 main current and the parts are in position, as shown in full lines, it is desired to stop the car, the lever H, carrying the devices for collecting or taking the current from the conductors, will be raised to the position indicated in dotted lines. The raising of the lever to this position results in simultaneously breaking circuit through both sections of the double solenoid, and the spring S will 130

therefore hold the switch in its normal position. To start the car again it is only necessary to restore the lever to the position shown in full lines.

5 The numerals 51', 52', 53', 54', and 55' indicate conductors over which a circuit may be completed from the accumulators for operating electric brakes, for maintaining electric lights, for operating electric signals, for 10 applying power to assist the main current on ascending grades, or for any other desired purpose for which a steady and reliable current is required. A main or external working-circuit having been established, sub-circuits in multiple are may be derived in any 15 convenient manner.

I have stated that the lever II may be utilized as the lever for bringing the collectors into or out of contact with the conducting-rails, and this will be understood by referring to Figs. 4 and 6, in which the collectors are illustrated rather conventionally than practically, but with sufficient clearness to show their adjustability and function of making electrical connection between the conducting-rails and the devices on the cars.

In Fig. 4 the collector-arms *t t* are made of metal and separated from each other by non-conducting blocks *t' t'*. At their lower ends 20 they are provided with metallic friction-wheels *t'' t''* to come in contact with the conducting-rails *d d*. The upper portions of the collector-arms are bent away from each other at right angles, and have their ends pivoted 25 in metallic hangers *t'' t''*, which are secured to the bottom of the car by the bolts 16 16'. From the upper horizontal portion of one of the collector-arms projects obliquely a short arm *t'*, which is by a rod connected with the 30 bent lower end of the lever II, pivoted at *h*. By operating the lever II, which may be provided with suitable stops or latching devices in the well-known manner, the collectors may be raised out of or lowered into contact with 35 the conducting-rails.

I have stated that the accumulators are sometimes used to propel the cars upon branches, extensions, or sidings of railways beyond the points at which the conducting-rails terminate. In the sectional view Fig. 5 I have shown a portion of a railway at *Y*, where the conducting-rails terminate, the letter *D* indicating the terminal of one of the 40 conducting-rails, and the letter *Y'* indicating the portion of the railway beyond the same. The end of the conduit is at the point *X*, and of course the collectors must be raised from the conduit in order that the car may travel upon that portion of the track where there is 45 no conduit, and in order that the collectors may be so raised the curb-plates *b* of the conduit are provided with doors or flaps *c*, (in full lines in Fig. 5 and raised in dotted lines in Fig. 6,) which may be raised to permit the 60 collectors to be withdrawn from the conduit and folded under the car, as shown in Fig. 6,

which may be considered as a partial longitudinal section of Fig. 4.

In Fig. 5 I have shown the accumulator-sections 19 and 27 as arranged under the 70 seats *C' C'* on opposite sides of the car. I have not numbered all of the conductors in this figure, as the placing of the numbers would tend to confusion, and the principle is so thoroughly illustrated in Fig. 7 that the 75 mere mechanical arrangement of the various conductors and devices will be easily within the skill of any person familiar with electrical constructions.

Having now thus fully described my invention, I wish it to be understood that I do not confine myself to any of the specific constructions shown in my drawings, but reserve to myself the right to vary the same in any manner for the better carrying out of the 85 principles of the invention without departing from the true spirit and scope thereof.

What I claim is—

1. In an electrical-railway system, the combination, with the conducting-rails and automatic switches for cutting sections of said conducting-rails out of circuit, of one or more 90 cars arranged to run upon the railway, a motor upon each of said cars connected with its 95 collectors arranged to communicate electrical current from the conducting-rails to the motor, secondary or accumulating batteries located on the cars, switching devices and conductors arranged to connect the collectors 100 with said secondary or accumulating batteries for charging the same, automatic devices for disconnecting said batteries from the charging-circuit when fully charged, and automatic switching devices for connecting 105 said secondary or accumulating batteries with the motor when the supply of current from the conducting-rails is cut off, essentially as set forth.

2. In an electrical railway, the combination of the main charged circuit formed in part by the conducting-rails, the car having the motor and secondary batteries mounted thereon and connected with the charged circuit in multiple are, and automatic switch 115 devices for cutting out the batteries when charged and for reconnecting said batteries in the charged circuit when wholly or partly exhausted by leakage or use, substantially as 120 described.

3. In an electrical railway, the combination of the main charged circuit formed in part by the conducting-rails, the car having the motor and secondary batteries mounted thereon and connected with the charged circuit in multiple are, automatic switch 125 devices for cutting out the batteries when charged, a working-circuit containing the batteries and motor, and switching devices for cutting said motor out of the charged circuit 130 and placing it in the working-circuit, substantially as described.

4. In an electrical railway, the combination of a main circuit, part of which is formed by the conducting-rails electrically charged from a stationary source of electricity, a motor-car having collectors mounted thereon for connecting the motor with and disconnecting it from the main circuit, with secondary batteries arranged upon the car to be charged from a branch of the main circuit, an electrically-operated switch controlled by currents from the main circuit and from the secondary battery for connecting the latter with the motor when the main current fails, a switch connected with the collectors for withdrawing the currents from the electrically-operated switch when the main circuit is broken, and another electrically-operated switch for simultaneously disconnecting the motor from the secondary battery, substantially as described.
5. In an electrical railway, the combination of the main circuit, the conducting-rails forming a part thereof, the car, the secondary batteries and motor mounted thereon, a switch, and a double solenoid for operating the same to cut the batteries and motor out of the main circuit upon a failure of current, one coil of said solenoid being in the main circuit and the other in a derived circuit with the secondary batteries, substantially as described.
6. The combination, with the main charging-circuit, a secondary battery or batteries, and an electromotor interposed therein in multiple arc, of a switch in said circuit arranged to interpose the batteries in the circuit with the motor and to sever the main circuit, and an electro-magnetic device operating upon a failure of current in the main charging-circuit to operate the switch and cause the operations mentioned, substantially as described.
7. The combination, with the main charging-circuit, the motor and a secondary battery or batteries coupled therein, and a switch arranged when operated to break the main circuit and couple the motor and batteries in circuit together, of a double solenoid for controlling said switch, one coil of said solenoid being coupled in the main circuit and the other in a circuit from the secondary battery,

whereby upon a failure of current in the main charging-circuit the switch will be operated and the operations mentioned will take place, substantially as described.

8. The combination, with the main charging-circuit, the motor and secondary battery or batteries coupled therein, and a switch arranged when operated to break the main circuit and couple the motor and batteries in circuit together, of a double solenoid for controlling said switch, each coil of said solenoid being coupled in an independent circuit, a switch controlling both the solenoid-circuits, so that they may both be manipulated simultaneously, thus preventing the operation of the main-circuit switch.

9. In an electrical railway, the combination, with the main charging-circuit formed in part by the conducting-rails, the motor and secondary battery or batteries coupled therein, and a switch arranged when operated to break the main circuit and interpose the motor and battery in circuit together, of a double solenoid for controlling the said switch, each coil of said solenoid being coupled in an independent circuit, the current-collectors, and switches connected with the current-collectors arranged in both said circuits, so that when the collectors are moved out of contact with the rails the solenoid-circuits will be simultaneously operated and the switch controlled thereby remain undisturbed, substantially as described.

10. The combination, with the main charging-circuit, of the motor and secondary battery or batteries coupled in said circuit in multiple arc, automatic switch devices for cutting out the batteries when charged, a working-circuit containing the batteries and motor, and switching devices for cutting said motor out of the charging-circuit and placing it in the working-circuit, substantially as described.

In testimony whereof I affix my signature, in presence of two witnesses, this 29th day of December, 1885.

ELIAS E. RIES.
